[57] CLAIM

The ornamental design for a handle for a beverage can,
as shown and described.

DESCRIPTION

FIG. 1 is a perspective view of a handle for a beverage can showing our new design;

FIG. 2 is a right side elevational view thereof, the left side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.
